UNITED STATES PATENT OFFICE.

HENRY LEPAK, OF MINNEAPOLIS, MINNESOTA.

MOP-WRINGING APPARATUS.

1,184,543.

Specification of Letters Patent. Patented May 23, 1916.

Application filed March 17, 1916. Serial No. 84,874.

To all whom it may concern:

Be it known that I, HENRY LEPAK, a citizen of the United States, residing at Minneapolis, in the county of Hennepin and State 5 of Minnesota, have invented new and useful Improvements in Mop-Wringing Apparatus, of which the following is a specification.

This invention relates to certain new and useful improvements in mop wringing 10 apparatus.

An object of the invention is to provide a mop wringing apparatus of a simple and novel construction which may be operated by the pressure of the foot of the operator 15 upon a suitable lever and which will so engage with the mop as to effectively press the same to wring all of the water therefrom.

Another object of the invention is to produce a mop wringer including a receptacle 20 for the water and provided with a hood member within which is arranged a press that is subject to a movement in the direction of the hood to engage with one of the 25 walls thereof as well as being subjected to a limited longitudinal movement with relation to the hood so that the press will so engage with the mop as to effectively compress the water therefrom when the said 30 press is operated.

A further object of the invention is to construct an apparatus of this class which shall embody the desirable features of simplicity, cheapness, ease in application and 35 efficiency in operation.

With the above and other objects in view the improvement resides in the construction, combination and arrangement of parts set forth in the following specification and falling 40 within the scope of the appended claims.

In the drawings: Figure 1 is a perspective view of a mop press or wringer constructed in accordance with the present invention. Fig. 2 is a central vertical longitudinal sectional view through the same, Fig. 3 is a transverse sectional view approximately on the line 3-3 of Fig. 2, Fig. 4 is a perspective view of the press with the slide member connected thereto, and Fig. 5 is a 50 similar view of the hood looking toward the interior thereof.

In carrying out my invention I employ a pail or receptacle 1 which is preferably rectangular and which is provided with a 55 suitable pivoted handle or bail 2.

The numeral 3 designates what I term the

hood member of my device, and this member is so constructed as to be removably secured within the pail, whereby said hood and the presser member associated therewith and 60 hereinafter to be referred to, may be employed in connection with pails or receptacles of other constructions than that illustrated in the drawings.

The hood 3 includes a flat top 4 and right 65 angular sides 5. The sides 5 extend beyond the lower or inner end of the top, and the said end of the top is bent downwardly or otherwise provided with a flange which extends between the sides, the said flange being indicated by the numeral 6. The hood is adapted to be arranged in the pail or receptacle 1 so that the lower ends of its sides will contact with one of the end walls 70 of the receptacle, and preferably the upper edges of the said side walls at the ends thereof are cut inwardly, as indicated by the numerals 7, and these edges resting upon one of the ends of a receptacle assist in maintaining the hood at an angle in the receptacle whereby the outer end or mouth of the hood may be disposed above the receptacle, 75 as illustrated in the drawings.

The sides 5, at the outer corners of the hood are provided with alining openings 80 which register with similar openings in the sides of the receptacle 1, and passing through the registering openings is a pivot rod 8. This rod has arranged thereon a sleeve 9 which is adapted to contact with the inner 85 faces of the sides of the hood to hold the same against the sides of the receptacle, and the ends of the rod project beyond the sides of the receptacle.

The top 4 of the hood at a suitable distance from the mouth thereof is formed with a transverse slot 10, and the opposite walls provided by the said slot are formed with outwardly extending flanges 11-11 which serve to materially strengthen the hood as well as provide walls for a slide member 12 which passes through the slot 10 between the sides of the hood. The upper edge of the slide 12 is extended laterally, as at 13-13, and the portions 13 not only 100 rest upon the top of the hood but project laterally therefrom beyond the sides of the receptacle 1. These extending ends of the members 13 are bent upon themselves or otherwise formed each with an eye 14. 110

The lower corners of the slide 12 are preferably notched and the inner or lower

edge of said slide is preferably bent upon itself to provide a barrel 15 through which is passed a pivot rod 16 that also passes through alining openings in the longitudinal members 17 of the substantially rectangular frame of the press member 18. The inner connecting member 19 of the frame of the press 18 is surrounded by a strap 20 that is secured to the flange 6 as well as to the underface of the top 4 of the hood member 3, and this strap is adapted to limit the lateral movement of the press between the sides of the hood 3. The press 18 includes a flat plate 21 which may be in the nature of a foraminous member or may be otherwise provided with spaced openings 22, and this plate is disposed upon the frame forward of the slide 12 and terminates approximately in a line with the outer edges of the hood. The weight of the press at the forward or outer end thereof is sufficient to tilt the same downwardly with respect to the receptacle 1, so that the said forward end of the frame of the press normally rests upon the sleeve 9 of the pivot rod 8.

The operating lever is indicated by the numeral 23 and comprises a substantially U-shaped member, the arms of which being disposed upon the opposite sides of the receptacle 1 and each of said arms is provided with an ear 24 having an opening through which the extending ends of the pivot rod 8 pass, and the said ends of the rod may be threaded and provided with nuts, or the said ends may be formed with heads and bent in any other desired manner arranged to secure the same upon the ends of the rod. The inner ends of the arms of the operating lever have each loosely connected therewith a link 25, each of the links being preferably in the nature of a rod having offset ends and the free offset end of each of the links is received in one of the eyes 14 of the widened or laterally extending upper portion 13 of the slide 12.

The connecting member for the U-shaped operating member indicated for distinction by the numeral 26 has formed thereon a pedal extension 27 which is adapted to accommodate one of the feet of the operator, while the end of the receptacle 1 opposite that which is straddled by the operating lever and at its lower edge is provided with an outwardly extending lug or flange 28 to receive the other foot of the operator whereby the receptacle is steadied during the actuation of the apparatus.

By reference to the drawings it will be seen that the operating lever is normally retained at an outward and upward angle with relation to the receptacle 1 and also that the press plate 21 is arranged at an angle with respect to the inclined top of the hood 3, so that a flaring mouth is provided

for the reception of the mop, and that the oppositely inclined slide member 12 provides the rear wall for the hood which serves to limit the inward movement of the hood.

From the above description, taken in connection with the accompanying drawings, the simplicity of the device as well as the advantages thereof will, it is thought, be perfectly apparent to those skilled in the art to which such invention appertains without further detailed description.

Having thus described the invention, what I claim is:

1. The combination with a receptacle, of a hood member arranged angularly in the receptacle so that its upper end extends above the receptacle and connected with the said receptacle, a press member arranged to move laterally between the sides of the hood, a slide member loosely connected with the press member and extending through an opening in the top of the hood, and a yoke-shaped operating member pivotally secured to the sides of the receptacle and having a connection with the slide.

2. The combination with a receptacle, of a hood member including a top and sides, said sides having their edges beveled, and the said hood being arranged in the receptacle to permit of its beveled edges contacting with one of the edges of the receptacle to sustain the hood at an angle with relation to the receptacle, and means for sustaining the said hood upon the receptacle, a press member including a frame arranged between the sides of the receptacle, a strap member upon the hood surrounding the inner member of the frame, and the connecting means for the hood providing a support for the outer member of the frame, a slideable plate passing through an opening in the top of the hood and pivotally connected with the frame of the press member, a yoke-shaped operating lever having its side arms pivotally connected to the receptacle, and link connections between the arms of the said lever and the slide.

3. The combination with a receptacle, of a hood member arranged angularly in the receptacle and extending above the receptacle, a pivot member passing through the sides of the receptacle and through the sides of the hood, a barrel upon the pivot member contacting with the sides of the hood, a frame arranged longitudinally between the sides of the hood and having one of its ends resting upon the barrel, a strap connected with the hood and surrounding the second or inner end of the frame, a reticulated plate upon the frame, at the outer portion thereof, a slideable plate passing through an opening in the top of the hood and connected with the frame at the inner end of the reticulated plate, a yoke-shaped operating

lever having its arms provided with journal openings to receive the ends of the connecting rod for the hood, a pedal member upon the connecting member of the yoke, and link connections between the arms of the yoke and the slidable plate.

4. The combination with a substantially rectangular receptacle, of a hood member arranged angularly of the receptacle and 10 projecting thereabove, a pivot rod passing through the sides of the receptacle and the sides of the hood, a barrel upon a pivot rod between the sides of the hood, a longitudinally movable frame arranged angularly between the sides of the hood, a strap member connected with the hood and engaging the inner connecting member of the 15 frame, a flat reticulated plate upon the

frame, at the outer portion thereof, a slideable plate passing through an opening in 20 the top of the hood and loosely connected with the frame at the inner end of the reticulated plate, said slideable plate having its outer corners extending laterally over the edges of the receptacle, a yoke-shaped 25 operating member having its arms provided with ears, a pedal upon the yoke, and link members connecting the ends of the arms of the yoke with the extending corners of the slideable plate.

In testimony whereof I affix my signature in presence of two witnesses.

HENRY LEPAK.
